UNITED STATES PATENT OFFICE.

CHARLES F. ARROTT, OF ALLEGHENY, PENNSYLVANIA.

DESIGN FOR A LEG FOR BATH-TUBS.

SPECIFICATION forming part of Design No. 27,599, dated August 31, 1897.

Application filed July 22, 1897. Serial No. 645,599. Term of patent 14 years.

To all whom it may concern:

Be it known that I, CHARLES F. ARROTT, a citizen of the United States, residing at Allegheny, in the county of Allegheny and State of Pennsylvania, have invented a Design for the Legs or Supports of Bath-Tubs, &c.; and I do hereby declare the following to be a full, clear, and exact description of the invention, such as will enable others skilled in the art to which it appertains to make and use the same.

This invention has relation to designs for legs or supports for bath-tubs, &c.; and it consists in a leg or support of the contour and configuration herein described and illustrated.

Figure 1 of the accompanying drawings is a front view, and Fig. 2 a side view, of a leg or support embracing my design.

The leg or support comprises the foot *a*, the standard *b*, and the head *c*. The standard *b* is of nearly uniform width for about half the length of the support and is then widened out on oppositely-curved lines to meet the head or tub-sustaining portion *c*, which is

abrubtly shouldered at *c'c'*. From the points *c'c'* toward the front of the support ornamental scrolls *d* are described, and between the terminals of these scrolls flutings *e* are formed. Below the head or capital a rounded panel *f* is formed in the front of the support, and underneath such panel an ornamental scroll *g* appears. Ornamental flanges or beads *h* are formed on the side edges of the support, and these merge into and produce scrolls *i* at the foot of the support, as shown.

The contour of the foot of the leg or support is shown in Fig. 2.

Having thus described my invention, I claim—

The design for a leg or support as herein shown and described.

In testimony whereof I affix my signature in presence of two witnesses.

CHAS. F. ARROTT.
